ROTARY PUMPS

Robert A. Hill and Howard M. Tomasko, Minneapolis, Minn., assignors to Waterous Company, St. Paul, Minn., a corporation of Minnesota
Original application Jan. 20, 1960, Ser. No. 3,551, now Patent No. 3,106,166, dated Oct. 8, 1963. Divided and this application July 16, 1962, Ser. No. 209,839
1 Claim. (Cl. 103—126)

This invention relates to an improvement in rotary pumps, and deals particularly with a means of hydraulically balancing pump rotors.

In the operation of rotary pumps, the rotors do not at all times remain centered between the end plates of the pump. The friction between the ends of the rotors and the end plates causes the engaging parts to wear, and to cause added resistance to the rotation of the rotors. Furthermore, when the rotors are centered, there is usually enough leakage between the rotors and the end plates to assist in lubricating the shaft seals. When the rotors move axially against one end plate, this leakage is reduced or eliminated, thus preventing the liquid from reaching the seals in this end plate.

It is an object of the present invention to provide a means of hydraulically balancing the rotors of rotary pumps to obviate the previous difficulties. This is accomplished without appreciably increasing the cost of production, resulting in a better product at virtually no additional cost.

A feature of this invention resides in providing a groove in each end plate leading from the discharge side of the pump to the seal chambers in the end plates. With this arrangement, when a rotor shaft moves axially until the rotor rubs against the end plate, the clearance between the rotor and end plate is reduced to zero, and the pressure in the seal chamber of the end plate engaged will be essentially equal to the pump discharge pressure. At the same time, the clearance between the other end of the rotor and the adjacent end plate will increase, allowing liquid to bleed readily from the seal chamber to the suction side of the pump. Thus the pressure in this second seal chamber will be reduced below pump discharge pressure. This variation in pressure in the seal chambers creates an end thrust causing the rotor to return to a central position.

This application is a divisional application of our previously filed patent for Pretimed Three-Lobed Rotary Pump, issued October 8, 1963, as Patent 3,106,166.

These and other objects and novel features of the present invention will be more clearly and fully set forth in the following specification and claim.

In the drawings forming a part of the specification;

FIGURE 1 is a vertical sectional view of a rotary pump showing the general form of construction thereof.

FIGURE 2 is a cross-sectional view of the pump shown in FIGURE 1, the position of the section being indicated by the line 2—2 of FIGURE 1.

FIGURE 3 is an enlarged sectional view of one of the rotor seals.

The rotary pump is indicated in general by the letter A. The pump includes a housing 10 having upper and lower arcuate portions 11 and 12 which form intersecting rotor chambers 13 and 14 designed to accommodate three-lobed rotors 15 and 16 respectively. The rotors 15 and 16 are mounted upon supporting shafts 17 and 19 respectively. As is usual in pumps of this type, the lobes of the rotors engage in the hollow portions between the lobes of the cooperating rotor to provide a minimum of leakage between the two rotors.

The housing 10 includes an inlet passage 20 and an

2

outlet passage 21 in communication with the rotor chambers 13 and 14. The fluid being pumped enters the inlet 20, is carried between the rotor lobes and the arcuate walls 11 and 12 and are discharged through the discharge passage 21. Intermediate the ends of the rotors, a by-pass passage including passage portions 22 and 23 extend from the discharge 21 to the inlet 20. A cylindrical passage 24 terminating in a valve seat 25 connects the passage portions 22 and 23. A pressure relief valve 26 is slidably supported in the cylindrical passage 24 and includes a beveled peripheral flange 27 designed to engage against the valve seat 25.

The relief valve 26 includes an axial boss 29. A plug 30 is threaded into an opening 31 in axial alignment with the valve 26. The plug 30 is provided with an axial socket 32 in opposed relation to the valve 26. A spring 33 is interposed between the base of the socket 32 and the flange 27 of the valve 26. One end of the spring 33 is held in place by the walls of the socket 32 while the other end of the spring encircles the boss 29 and is held in position thereby.

The cylindrical skirt 34 of the valve 26 which slides within the cylindrical passage 24 is notched as indicated at 35 to points in closely spaced relation to the flange 27. Thus, when the relief valve is moved due to abnormal pressures in the discharge passage, fluid may flow through the notches 35 in the hollow skirt 34 and into the passage 23 connected to the pump inlet 20.

The ends of the housing 10 are closed by end plates 36 and 37 which are properly located by dowel pins 39 which extend through the end plates and into the housing 10. Bearing supporting plates 40 and 41 are secured in face contact with the end plates 36 and 37 and are also located relative to the end plates and the pump housing by suitable means such as by the dowel pins 39. The bearing supporting plates 40 and 41 are apertured to accommodate a pair of sealed bearings 42 and 43, the apertures being indicated by the numerals 44 and 45. Seals 46 and 47 are supported in grooves 49 and 50 respectively to seal the outer races of the bearings 42 and 43 relative to the walls of the apertures 44 and 45. The inner races of the bearings may be sealed relative to the shaft 17.

The bearing supporting plates 40 and 41 are also provided with a second pair of aligned apertures 51 and 52 which support sealed bearings 53 and 54 which support the shaft 19. The outer races of the bearings 53 and 54 are sealed relative to the apertures 51 and 52 by seals 55 and 56.

The ends of the rotors 15 and 16 are provided with axial sockets 57 and 59 respectively which include sealing units. As all of the seals are of identical form, the parts will be given similar identification numbers. Sealing rings 60 are slidably engaged in sockets 61 and 62 coaxial with the shafts 17 and 19 in the end plates 36 and 37. The rings 60 are sealed relative to the walls of the socket by O rings 63 located in the externally grooved surface of the rings 60. A sealing ring 64 encircles the shaft 17 or 19 and is sealed relative thereto by O rings 65. The sealing ring 64 is urged into sealing relation with the ring 60 by means of a spring 66 interposed between the sealing ring 64 and the base of the socket 57 or 59.

A cover plate 67 overlies the bearing supporting plate 40 and is connected thereto by bolts 67' which extend through the cover plate, through the bearing supporting plate, the end plate, and into the pump housing 10. A gear housing 69 including an end wall 70, a peripheral wall 71 and an outwardly extending mounting flange 72 is connected to the other end of the pump housing by means of bolts 73 which extend through the flange 72, through the bearing supporting plate 41, the end plate 37, and into the end of the housing 10. The end wall 70 is

provided with an opening 74 containing a seal 75 to accommodate the projecting end 76 of the drive shaft 17.

Gears 77 and 79 are pinned to the shaft 17 and 19 respectively by pairs of taper pins 80 and 81 extending diametrically to apertures 82 and 83 in axially spaced relation in the gears 77 and 79. The gears 77 and 79 are provided with angularly spaced teeth.

In FIGURE 2 of the drawings a groove 159 is shown in the end plate 36 forming an end wall of the pump. A similar groove is provided in the end plate 37. These grooves lead from the discharge side of the pump to the seal chambers or sockets 57 and 59, subjecting these chambers substantially to discharge pressure. If the rotor moves axially until it rubs against the end plate the clearance at that end will be reduced to zero and the pressure in the seal chamber will be substantially equal to discharge pressure. At the other end, however, the clearance between the rotor and the end plate will increase to a maximum, allowing liquid to bleed readily from the seal chamber to the suction side of the pump, reducing the pressure in the seal chamber to somewhat below discharge pressure. This results in an end thrust tending to move the rotor to central position where it has equal clearance with each end plate.

In accordance with the patent statutes, we have described the principles of construction and operation of our improvement in rotary pumps, and while we have endeavored to set forth the best embodiment thereof, we desire to have it understood that changes may be made within the scope of the following claim without departing from the spirit of our invention.

We claim:

A rotary pump including a pair of lobed intermeshing rotors, rotor shafts in said rotors, a housing defining intersecting rotor chambers enclosing said rotors, said housing including a discharge outlet and a suction inlet on opposite sides of the intermeshing portions of said lobes, end plates closing the ends of said housing, means connected to said end plates supporting said shafts in

parallel relation, flat ends on said rotors substantially in sealing relation with said end plates, said rotors being axially slideable to vary the spacing between the rotor ends and said end plates, said rotors having axial sockets in the ends thereof, the inner surfaces of said end plates including sockets encircling said shafts, said inner surfaces also including grooves leading from said discharge outlet side of said housing to said sockets, all of said sockets having a diameter smaller than the roots of the lobes of said rotors, a sealing ring in each of said sockets in said end plates, and sealed relative thereto, a co-operable sealing ring in each axial socket in said rotor and engaging the first named sealing rings with a running fit, means urging said co-operable sealing rings and first named sealing rings into engagement, said co-operable sealing rings being sealed relative to their shafts, whereby pressure in said sockets will assist in urging said sealing rings into engagement, and whereby axial movement of one rotor toward one end plate, increasing the distance between said one rotor and the other said end plate will permit fluid in the socket in the other said end plate to flow to the suction inlet side of the housing and lower the fluid pressure in the socket in said other end plate until the rotor is forced to return to a position centralized between said end plates.
